UNITED STATES PATENT OFFICE.

HENRY D. POWNALL, OF CANTON, OHIO.

FRACTURE BED.

Application filed June 14, 1926. Serial No. 115,882.

The invention relates to fracture beds for use in hospitals and the like, and more particularly for the use of patients suffering with one or more fractures in one or both 5 legs.

Heretofore a patient having one or more leg fractures, when confined to a bed of the usual type, has found it very difficult to rest comfortably, due to the difficulty in moving 10 the fractured members and coincidental difficulties have been encountered in nursing and treating the patient.

The foregoing difficulties in making the patient comfortable and in nursing and 15 treating him have been marked when one leg has been affected, and in the case when both legs are fractured, the difficulties are greatly enhanced.

The objects of the present invention are to 20 provide a fracture bed having cooperating means which enable the positioning and adjustment of a patient's fractured members and the remainder of his body in desired relationships with each other, and adapted for 25 the patient's comfort and ease of nursing and treatment.

These objects are attained by the use of a construction and arrangement which, in 30 general terms may include a stationary top frame secured as at the top ends of the bed corner posts, a movable crane frame below the top frame and movably supported therefrom, a stretcher adjustably supported below the crane frame and normally resting upon 35 the bed mattress, a plurality of slings for the fractured members and other parts of the patient's body movably supported from the crane frame and intermediate the crane frame and the stretcher, a back rest hinged 40 to the stretcher frame and adjustably supported from the crane frame, and means for controlling and moving the foregoing crane frame, slings, and back rest, some of the means being operable by the patient.

45 A preferred embodiment of the invention is illustrated in the accompanying drawings, forming part hereof, in which—

Figure 1 is a side elevation of the improved fracture bed, the adjustable leg slings being illustrated as in use on a patient, and the adjustable body slings being illustrated 50 in full lines as for normal resting of the patient upon the stretcher, and in dotted lines as ready for lifting the patient's body up 55 from the stretcher;

Fig. 2, an end elevation of the fracture bed without a patient;

Fig. 3, a top plan view of the bed;

Fig. 4, a development of one of the body slings; and

Fig. 5, a fragmentary section as on line 5—5, Fig. 3, of one of the adjustable, longitudinal bars provided with strap handles by means of which the patient may raise himself.

Similar numerals refer to similar parts throughout the drawings.

The improved fracture bed indicated generally at 10, includes a stationary top frame, indicated generally at 11, secured as at the top ends 12 of bed corner posts 13, and a movable crane frame indicated generally at 14 below the top frame and movably supported therefrom as by means of cables 15, pivotally secured at their lower ends 15' as by means of eye bolts 16 to the crane frame 14, the cables extending upwards and over pulleys 17 suitably journaled in the frame 11, and laterally therefrom over pulleys 18 secured at one end of the frame 11, and downward therefrom to winding drums 19 suitably keyed upon a preferably horizontal shaft 20, journaled in brackets 21 and 21' suitably mounted upon one pair of the end corner posts.

The bracket 21' also carries a wheel and worm reduction gear, indicated generally at 22^a, the wheel being keyed to the shaft 20 and the worm having an outwardly extending shaft 23^a keyed thereto, which carries upon its outer end a sprocket wheel 24 operatively connected by means of a chain 25 with a sprocket pinion 26 suitably journaled in a bracket 27 mounted at one of the corner posts, the sprocket pinion 26 being provided with an outward extension 28 of its shaft which is keyed to an operating crank 29.

A stretcher 30 is adjustably supported below the crane frame 14 as by means of ropes 31 pivotally secured at their lower ends to the corners of the stretcher as by means of harness snaps 32 removably connected to rings 33 welded to the stretcher frame, the stretcher frame including rectangularly arranged tubes 34 and 35, secured to each other.

The ropes 31 are pivotally and adjustably secured to the crane frame 14 as by means of eye bolts 36 having their eyes connected to the upper ends of the ropes 31 and being supported upon the crane frame by means

of the adjustable nuts 37 screwed upon the bolt ends of the eye bolts, the bolts extending through suitable apertures provided in the frame 14.

5 The adjustment of the nuts 37 is such that the stretcher 30 normally rests upon the mattress 38, which in turn is supported by bed springs 39 in a usual manner.

10 A plurality of slings including leg slings 40, and body slings 41, are adjustably and movably supported from the crane frame, intermediate the crane frame and the stretcher. The crane frame 14 may include longitudinal angle side members 42 secured at their ends 15 to brackets 43 slidably mounted upon the corner posts 13, and secured to crane frame end angle members 44.

10 The angle members 42 are preferably provided with a plurality of longitudinally spaced apertures 45 for receiving pins 46 which adjustably secure the various cross crane members of the device to the crane frame members 42.

25 These cross crane members include a shaft 47 mounted in bearings 48 and carrying the leg sling supporting pulleys 49 slidably journaled thereon.

30 Other cross crane members include a plurality of cross crane U-beams 50 adjustably secured at their ends 50' and 50'' to the frame members 42 as by means of pins 46.

35 One end 50'' of each cross beam curves upwardly and angularly to the cross beam and supports a worm and wheel reduction gear 22, the worm shaft 23 extending longitudinally of the bed and carrying on its outer end a crank 51, and the wheel axis being parallel with the cross U-beams 50 and being keyed to a cross sling drum shaft 52 journaled at its other end in an angular extension of the U-beam end 50'. Each shaft 52 is provided with a plurality of drums 53 keyed thereon.

40 Upon the cross U-beam 50 nearest the shaft 47, a pair of laterally adjustable hand wheel brackets 54 are mounted as by means of pins 55 interchangeably fitting in a plurality of apertures 56 provided in one leg of the U-beam.

45 Each bracket 54 carries at its upper end a journal 57 through which a longitudinally extending screw 58 is slidably keyed, the screw 58 being upset at its end 58' nearest the shaft 47, and provided with an aperture 59.

50 The threaded hand wheel 60 which may be provided with a handle 61, is screwed upon the other end 58'' of each screw 58, and the hand wheel reacts against the journal 57 of the bracket 54.

55 A rope 62 is secured at one end to the aperture 59 in the upset end 58' of each screw 58, and passes downwardly over one of the pulleys 49 upon the shaft 47, and is connected 60 at its lower end with a depending adjust-

able bracket indicated generally at 63, supporting a leg sling 40.

Each leg sling 40 may include a fabric band 64 provided at its longitudinal edges with longitudinal bars 65 secured to the band, and having slidably mounted thereon pairs of harness snaps 32 which are hooked in eyes 66 of outwardly extending lugs 67 of each of a pair of cross bars 68.

The cross bars 68 are connected by a lower 75 rod 69 supported upon a roller 70 mounted at the lower end of a depending yoke 71 to which the end of the rope 62 is secured.

Above the rod 69 and parallel therewith, a longitudinal screw 72 is journaled for rotation in the cross bar 68 and provided at one end with a thumb nut 73, and the screw 72 is screwed in a threaded aperture in the yoke 71 above the roller 70.

Ropes 74 are secured at their upper ends 85 to the drums 53 of the two shafts 52 nearest the leg slings, and provided at their lower ends with harness snaps 32 for removable connection with the supporting rings 75 of the body slings 41.

90 The drums 53 of the shaft 52 nearest the head of the bed, have secured thereto the upper ends of ropes 75' which are provided with hooks 76 at their lower ends, for removably hooking under the cross bar 77 of a 95 back rest 78 pivotally connected to the stretcher frame as at 79.

95 A cross angle 80 may be adjustably secured at its ends as by means of pins 46 intermediate the shaft 47 and the next adjacent U-cross beam 50. The cross angle 80 is provided with a pair of centrally located spaced U-bolts 81 depending therefrom, and each of the U cross beams 50 are provided with a lateral slot 82 in which journals 83 are removably mounted as by means of studs 84 passing through the slots and nuts 85 screwed upon the studs and resting upon washers 86 resting upon the U-beam.

100 The journals 83 depend from the studs 84 and the journal apertures are aligned with each other and with the depending U-bolts 81 providing supports for a pair of spaced longitudinal bars 87.

105 At any desired location along the bars 87, 110 strap handles 88 may be located and removably strapped around the bars 87 by means of buckles 89, providing adjustable means by which the patient may raise himself by grasping the handles with his hands.

110 As illustrated in Fig. 1, a patient X may have suffered fractures of both legs below the knee, and his legs as illustrated, have been set in casts 90.

115 In a type of fracture bed heretofore in use, 120 each leg has been supported from a stationary frame above the bed mattress by means of a single rope having its upper end tied to the frame and its lower end tied around splints in which the cast rested.

By this method of suspending the broken leg, a concentrated load was impressed upon the cast, and if the location of the supporting rope was not at the center of gravity of the 5 cast and leg, a very uncomfortable and ultimately painful over-balancing tendency of the cast and leg was set up, which caused either a pull or push on the thigh and body of the patient.

10 Moreover the discomfort and pain incident with a fracture of one leg thus suspended was more than doubly enhanced when both legs happened to be fractured and were suspended by single ropes, as heretofore described, since 15 it was then practically impossible to properly balance both legs at the same time. Moreover, even though an instantaneous balance were attained, any slight motion of the patient's body incident to treatment, nursing or mere 20 movement for comfort, would immediately unbalance the legs thus supported at concentrated points.

Moreover such a fracture bed was not provided with any means for lifting the body of 25 the patient while nursing or treating him or while changing the bed clothes and the like, and any such lifting had to be done by one or more attendants.

Moreover, the pivotal back rest usually provided, was not adapted for fine angular adjustment.

By the arrangement and construction of the fracture bed as heretofore described, the 35 leg slings 40 provide distributed supports for the casts and legs, and the slings, casts and legs may be balanced at will by manipulation of the thumb nut 73 either by the attendant or by the patient himself.

Moreover, the height of the sling 40 relative 40 to the mattress of the bed may be varied at will by manipulation of the hand wheel 60, thus enabling the legs to be maintained at all times in positions most comfortable to the patient and most conducive to rapid knitting 45 of the fractured bones.

By means of the ropes 74 wound about the drums 53 rotatable by operation of the crank handles 51 and having at their lower ends the harness snaps 32 which removably hook into 50 the ring 75 of the body slings 41, the patient's whole body may be lifted up at will from the stretcher and the mattress, enabling rearranging of the bed clothes, and nursing and treatment as desired.

55 By means of the ropes 75' wound about the drums 53 of the shaft 52 nearest the head end of the bed and provided at their lower ends with hooks 76 hooked under the cross bar 77 of the pivoted back rest 78, any angular adjustment may be made and maintained for the pivoted back rest; so that by the use of the lifting and balancing mechanism for the leg slings and the angular adjustment for the back rest, any desired relationship between 60 the positions of the patient's legs and the re-

maining portions of his body may be made and maintained.

The slings for the fractured members and the other parts of the patient's body and the adjustment for the pivoted back rest are all 70 operated by mechanism located on the adjustable crane frame 14 which may be elevated or lowered at will by turning crank handle 29, which through the heretofore described gearing will raise and lower the ropes 15 which 75 support the crane frame 14.

The stretcher 30 being supported by means of ropes 31 from the frame 14, may likewise be elevated or lowered with the frame 14 by operation of the handle 29, thereby enabling 80 turning or changing of the mattress 38, and the like.

An improved fracture bed embodying the invention herein and of the foregoing description has been used by a patient suffering 85 from fractures of both legs below the knee, following temporary and very uncomfortable and inconvenient use of an old style fracture bed heretofore described. The use of the improved fracture bed very materially 90 increased the comfort of the patient and facilitated nursing and treatment.

I claim:—

1. In a fracture bed and the like, an adjustably supported sling including a band, 95 a plurality of supporting links secured to each of opposite edges of the band, cross bars connecting opposite links, a rod connecting the cross bars, a yoke slidably supporting the rod, and means for adjusting the position 100 of the yoke on the rod.

2. In a fracture bed and the like, band means providing support for a fractured member substantially throughout the entire length of the fractured member, and means 105 for adjustably balancing the supporting means, and including a suspending member and screw means connecting the support with the suspending member and adapted for varying the longitudinal position of the support with reference to the suspending member.

3. In a fracture bed and the like, a bed frame, a movable frame mounted on the bed frame, a support for a fractured member 115 substantially throughout the entire length of the fractured member including band means, and means for adjustably raising and lowering the support and including a suspending member, a journal secured to the movable 120 frame, a screw longitudinally extending through the journal and slidably keyed to the journal, the screw being connected to the suspending member and a hand wheel threadably mounted on the screw and bearing against the 125 journal for producing longitudinal motion of the screw to raise and lower the support.

In testimony that I claim the above, I have hereunto subscribed my name.

HENRY D. POWNALL.
